J. M. HARGRAVE

RATCHET HAND TOOL

Filed Oct. 22, 1919

Inventor:

John M. Hargrave,

By *Word & Word*

Attorneys

UNITED STATES PATENT OFFICE.

JOHN M. HARGRAVE, OF CINCINNATI, OHIO.

RATCHET HAND TOOL.

Application filed October 22, 1919. Serial No. 332,514.

To all whom it may concern:

Be it known that I, JOHN M. HARGRAVE, a citizen of the United States, and residing at Cincinnati, in the county of Hamilton and State of Ohio, have invented a new and useful Improvement in Ratchet Hand Tools, of which the following specification is a full disclosure.

This invention relates to ratchet handles 10 for hand tools such as screw drivers and to devices of this class, operable in either forward or reverse direction of rotation, or rigidly connected with the shank of the tool.

An object of the invention is to provide 15 a pivoted latch or detent, that will lock the pawls either in or out of their operative positions with the ratchet, and the latch or detent so arranged and constructed that it will be sustained in its set position until again 20 manually operated by the user.

A further object is to provide an assembly 25 of the parts of the tool, whereby the same are held in their operative positions by a single fastening device, which forms a pivot for the latch or detent and holds the cover plate in position.

An additional object is to provide a form 30 of cover plate that will enclose all the working elements of the device and which will, by its formation and positioning, positively hold the tool shank engaged within the handle.

Other objects are to provide a handle, placed at a right angle to the long axis of 35 the tool, and to so position the locking and reversing means, that the lever of the same, when the said handle is held as in use, will be directly beneath the index finger of the operator, enabling him to readily set the 40 same to its various positions.

Other objects and advantages of my invention will appear in this specification and will be specifically pointed out in the claim hereunto appended, and reference to the 45 drawings, which form a part of my specification, will be made. Like numerals refer to corresponding parts throughout the drawings, in which:

Figure 1 is a side elevation, a portion of 50 the casing being broken away to expose a portion of one of the locking plates or pawls, and a portion of the spring coacting therewith.

Figure 2 is a central vertical section 55 through the handle of my device, the tool

and its ratchet wheel being shown in elevation.

Figure 3 is a cross-section through the tool shank and cover casing, on line 3-3 of Figure 2, the other parts being shown in 60 elevation.

Figure 4 is an elevation of the cover plate, and contiguous parts, the tool shank or stock being shown in section.

Figure 5 is a diagrammatic view showing 65 the angular relations of the pivoted latch or detent in one of its pawl cooperating positions, to its pivot and to one of the pawls.

Figure 6 is a face view of the head or base 70 for supporting the working elements.

In carrying out my invention, I provide a head or base portion 1, of substantially rectangular form, provided at one side with an outstanding cylindrical boss 2, designed to fit into a socket 3 of a handle 4, placed 75 at a right angle to the long axis of the tool, and the base portion is further provided on the same side with a relatively thin outstanding arcuate wing or web 5, continuous with the boss 2, projecting below the same, 80 and designed to enter a similarly shaped slot 6 of the handle 4 to which it is fastened by a cross-pin 7. The handle 4 thus may be made of wood although the head and handle portion may be integral and of the 85 same material.

The head 1 is bored at 8 for the reception of the ratchet wheel 9, as shown herein, formed as an integral part of the tool stock or bit 10, and the said head is counter-bored 90 at 11, for the reception of a reduced cylindrical projection 12 of the stock or bit 10. The head 1 has an inverted substantially T-shaped outstanding projection 13, to provide opposite pockets 14 for the rigid ratchet 95 plates or pawls 15 of rectangular form, coacting respectively at one of their extremities with the ratchet-wheel 9, and at the other, are shaped to provide knife edges 16 resting upon shoulders 17 of the T-shaped 100 projection 13.

As a result of the formation and positioning of the T-shaped projection 13, re-entrant spaces or pockets 14 are formed at each side thereof, for the reception of the 105 pawls 15, and of bowed springs 19, the springs coacting with said pawls to force them into engagement with the ratchet-wheel 9, when released by the detent.

The cover plate 20 has, in face view, the 110

form of an isosceles trapezoid, flush with the face end of the head, and is provided at its convergent sides with inturned flanges 21, socketed into the opposite sides of the head 1 by fitting into notches 22 at the top face of the base 1, and into similar notches 23 at the bottom face thereof. The inner sides of the inturned flanges 21 are parallel with the side faces of the T-shaped projection 13, and the cover plate as a whole forms, with the reentrant faces or pockets 14, a housing for the springs 19 and pawls 15. The upper portion of the cover-plate is provided with a semi-circular notch 24, designed to project into an annular groove 25, formed by the contiguous faces respectively of the ratchet wheel 9 and of a cylindrical grip portion of the stock 10, from which the tool projects, the upper portion of the cover-plate 20 acting to lock the said tool and its ratchet-wheel securely in assembled position.

The pawls 15 are alternately actuated for engagement with the ratchet-wheel 9, by a locking and reversing detent 30 of unique construction. Said detent represents a sheet metal stamping having a body portion 31 of substantially triangular configuration, and a handle portion 32, bent to project through an arcuate opening 33 in the cover-plate 20, and the said body portion 31 is drilled for the reception of a pivot-screw 34, threaded to coact with a similarly threaded opening 35 in the head 1. A washer 36 is interposed between the detent 30 and the cover-plate 20, and is provided with openings 37 and 38 respectively, for the reception of the pivot-screw 34, and for the handle portion 31 of the detent 30. This screw pivots the detent 30 and fastens the cover-plate in position; the said cover-plate in turn houses the detent and its co-related pawls and springs, and holds the parts together, allowing free rotation of the ratchet, but preventing axial movement thereof.

Referring to Figure 5 it will be discerned that the detent 30 is positioned centrally between the two pawls 15, and on each side of its central axis (a), and parallel to the axis 50 and equi-distant therefrom, the detent is

provided with side faces 40, the upper corners 41 producing knife edges which act to engage the pawls 15 and hold the same alternately out of engagement with the ratchet-wheel 9, and at such times are so related to the engaging side faces of the pawls 15 that the corners or knife edges contact the pawl side faces at a point below a line (b) drawn through the center of the detent pivot, the said line being at right angles to the pawl side faces and an acute angle (c) is thus formed between the line (d) drawn through the center of the pivot, and through the point of contact of the corners 41, and the side faces of the said pawls. By this arrangement the pressure of the springs upon the pawls tends always to lock the detent in operative position.

The corner 41 which is not in engagement with its pawl, contacts an undercut surface 44 of the head 1 to limit the rotation of the detent 30.

The pawls being rigid, non-flexible members and when engaged with the ratchet wheel act as a brace against rotation of the wheel and are capable of resisting heavy wheel turning strains.

Having described my invention, I claim:

In a device of the class described, a handle providing a counterbore, in one face thereof, a tool providing circumferential ratchet teeth adjacent one end thereof, said end and teeth rotatively stepped in said counterbore, with said tool at right angles to said handle, spring pressed pawls engageable simultaneously and independently with said ratchet teeth, pivoted means for controlling said pawls, and a cover enclosing and retaining said pawls, springs, and latch, and engaging the said ratchet teeth, to retain said tool in its counterbore, the pivot for said controlling means engaging and securing said cover.

In witness whereof, I hereunto subscribe my name, as attested by the two subscribing witnesses.

JOHN M. HARGRAVE.
